LINE RULING ATTACHMENT FOR
TYPEWRITERS

John Bosquet, New York, N. Y.

Application September 15, 1949; Serial No. 115,855

6 Claims. (Cl. 197—113)

1
The invention herein disclosed is a device for ruling lines on typewriters.

Objects of the invention are to provide a simple, inexpensive form of line ruling mechanism which may be quickly and easily applied as an attachment to a standard typewriter to form continuous lines, vertically or horizontally, as may be required.

Particular objects of the invention are to effect a quick connection of the line ruling mechanism with the typewriter, to draw a straight, accurate line and to enable this line to be raised or lowered as desired, to locate it in the line of the letters on the machine or to effect underlining of the written matter.

Other important objects of the invention are to provide the device in the form of a stylus approximately the size of an ordinary writing pen, so as to be conveniently handled and at the same time small enough to be entered into position and engaged with the type guide of a standard writing machine.

Other desirable objects attained by the invention and the novel features of construction, combination and relation of parts going into the make-up of the invention are set forth or will appear in the course of the following specification.

The drawing accompanying and forming part of the specification illustrates a present practical embodiment of the invention. Structure, however, may be modified and changed as regards the immediate illustration, all within the true intent and scope of the invention as hereinafter defined and claimed.

Fig. 1 in the drawing is a broken cross sectional view illustrating a form of the invention as applied to and used on an ordinary typewriting machine, parts of the latter being indicated to the extent of the platen and type guide in front of the platen;

Fig. 2 is a broken perspective view illustrating the ruling attachment as being approached to the type guide;

Fig. 3 is a front end elevation of the attachment;

Fig. 4 is a cross sectional view of the attachment on substantially the plane of line 4—4 of Fig. 1;

Fig. 5 is a horizontal sectional view of the supporting and guiding structure on substantially the plane of line 5—5 of Fig. 3.

In Fig. 1, the platen of a typewriting machine is indicated at 6 with a type guide 7 in the usual position in front of the same.

2
The guide 7 is usually constructed about as shown in Fig. 2, with forwardly extended fingers 8 spaced to afford a convergent throat or guideway 9 between the same for the type bars.

The present invention make use of this guide for locating and holding a ruling implement in engagement with the sheet on the platen.

Specifically the drawing or ruling implement is shown as a ball point pen 10 seated in an eccentric bore 11 in a cylindrical support 12 rotatably confined in a cylindrical barrel or casing 13.

The latter has a base structure to fit the companion fingers of the type guide, and this is shown in Fig. 3 as a dependent shoe 14 at the underside of the forward portion of the barrel convergently grooved in the opposite sides at 15 to slidily engage in the convergent guideway 9 of the type guide.

The tapered fit of the supporting shoe in the type guide centers and steadies the drawing implement and may be designed to limit the forward projection of the implement to prevent excessive pressure against the platen.

This construction affords a quick and easy way for engaging the implement in the machine and for holding it accurately in position while the carriage is shift horizontally for ruling horizontal lines, and rotated for ruling vertical lines.

The amount of pressure desired for ruling these lines may be governed by the hand holding the pen in position on the type guide, while the other hand is employed for shifting the carriage or rolling the platen.

The ball point pen is of particular advantage in enabling as much pressure as may be needed for ruling either horizontal or vertical lines and for drawing continuous lines just as freely with the carriage shifted horizontally in either direction or the platen rotated vertically in either direction.

The eccentric disposition of the pen in the mounting support enables lines to be drawn either in line with the letters, as for lining out or for connecting horizontally spaced letters or numbers, and for underlining or overlining printed subject matter.

To set the pen in these different positions there is provided, in the illustration, a spring clip 16 riveted or otherwise fixed at 17 to the plug 18 in the end of the eccentric bore 11, so that it may be used as a handle for rotating the cylinder 12 and eccentric pen in the stationary casing 13. The latter is shown as having cavities 19 for engagement by the end of the spring clip to yield-

ingly retain the pen in various positions of eccentric adjustment.

The pen with its mounting structure is of relatively small size so that it will readily go into the space left at the front of the platen and be easily engaged with the type guide. When not in use the pen may be laid aside and kept handy as a typewriter accessory. The pen itself may be a conventional ball point pen of proved construction and the mounting for the same may be produced at low cost, so the entire device may be wholly practical from a cost standpoint.

The sliding engagement and guiding of the pen in the type guide, in addition to definitely locating and holding the pen in proper position for ruling, allows for applying sufficient pressure to effect ruling of any usual number of carbon copies. In addition to straight lining either vertically or horizontally, the pen may be used to combine these lines to effect boxing of selected portions of typed subject matter.

In the form of construction shown in Fig. 1, the pen may be inserted in the front end of the eccentric bore 11. It is possible, however, to make the device so that the pen may be inserted into the holder or base portion from the back. In fact, the base may be made quite short, approximately the length of the sliding shoe portion 14, in which case this short base would have a bearing receiving the cylindrical support 12, and the latter would have an eccentric bore 11 into which the pen could be inserted from the back. In such a construction a spring detent such as shown at 16, could be carried by the cylindrical support and engage detent recesses in the supporting head structure, all of similar effect to the structure first disclosed.

The type guide illustrated at 7 is of a familiar, conventional design and the supporting base is shaped to correspond. It will be appreciated that for other forms of type guides the supporting base will be designed and constructed to complement and properly fit the special form of type guide.

The ball point pens used for ruling in the present invention, usually have a small vent at some place in the barrel of the pen. To avoid sealing off this vent when the pen is mounted in the holder, a vent of more or less equal size may be provided for the cavity in which the pen is located, such as a small passage shown at 20 extending through the plug 18 in the end of the pen receiving bore 11.

What is claimed is:

1. A ruling device for a typewriter of conventional design having a platen and a type bar guide in front of the platen and comprising a cylindrical casing having a mounting grooved in opposite sides to slidably engage in the type bar guide, a cylindrical support rotatably adjustable in said cylindrical casing, and a ball point pen mounted in eccentric relation in said cylindrical support and arranged to be thrust when said cylindrical casing is engaged with said type bar guide, into line ruling relation with said platen.

2. A ruling device for a typewriter of conventional design having a platen and a type bar guide in front of the platen and comprising a cylindrical casing having a mounting grooved in opposite sides to slidably engage in the type bar

guide, a cylindrical support rotatably adjustable in said cylindrical casing, a ball point pen mounted in eccentric relation in said cylindrical support and arranged to be thrust when said cylindrical casing is engaged with said type bar guide, into line ruling relation with said platen, and detent means for yieldingly retaining said cylindrical support in various positions of rotary adjustment in said casing.

10 3. A ruling device for a typewriter of conventional design having a platen and a type bar guide in front of the platen and comprising a cylindrical casing having a mounting grooved in opposite sides to slidably engage in the type bar guide, a cylindrical support rotatably adjustable in said cylindrical casing, a ball point pen mounted in eccentric relation in said cylindrical support and arranged to be thrust when said cylindrical casing is engaged with said type bar guide, into line ruling relation with said platen, and a spring clip on the outer end of said cylindrical support for rotating and retaining the same in various positions of adjustment in said casing.

15 4. A ruling attachment for a typewriter having a platen and a type guide having a convergent guideway and comprising a cylindrical casing, a shoe on the forward end portion of said casing convergently grooved in opposite sides to fit said convergent guideway in the type guide, a cylindrical support rotatably adjustable in said cylindrical casing, a writing implement mounted eccentrically in said rotatably adjustable support and means for effecting rotative adjustment of said support.

20 35 5. A ruling attachment for a typewriter having a platen and a type guide having a convergent guideway and comprising a cylindrical casing, a shoe on the forward end portion of said casing convergently grooved in opposite sides to fit said convergent guideway in the type guide, a cylindrical support rotatably adjustable in said cylindrical casing, a writing implement mounted eccentrically in said rotatably adjustable support and means for effecting rotative adjustment of said support, including a spring clip on the outer end of said support, said cylindrical casing having detent seats therein for yielding engagement by the end of said spring clip.

25 40 45 6. A ruling attachment for a typewriter having a platen and a type guide in front of the platen and comprising a support having means connectible in sliding engagement with said type guide, said support having a bore therein, a ball point pen inserted in said bore for cooperative relation with the platen and said bore having venting means for said ball point pen.
